(57) **CLAIM**

We claim the ornamental design for a combination car seat and stroller, as shown and described.

DESCRIPTION

FIG. 1 is a perspective view of a combination car seat and stroller showing our new design;

FIG. 2 is a front elevational view thereof;

FIG. 3 is a rear elevational view thereof;

FIG. 4 is a right side elevational view thereof, the left side elevational view being a mirror image thereof;

FIG. 5 is a top plan view thereof;

FIG. 6 is a bottom plan view thereof; and,

FIG. 7 is a left side elevational view showing the combination car seat and stroller in a car seat configuration with the legs thereof collapsed, all other views showing the combination car seat and stroller in a stroller configuration.

1 Claim, 6 Drawing Sheets

FIG. 1.

FIG. 2.

FIG. 3.

FIG. 6

FIG. 5

FIG. 7.
